UNITED STATES PATENT OFFICE.

THEODORE H. HABERKORN, OF DENVER, COLORADO.

GASEOUS-FUEL HEATER AND MIXER FOR INTERNAL-COMBUSTION ENGINES.

1,143,902.

Specification of Letters Patent. Patented June 22, 1915.

Application filed June 15, 1914. Serial No. 845,282.

To all whom it may concern:

Be it known that I, THEODORE H. HABERKORN, a citizen of the United States, residing at Denver, in the county of Denver and State of Colorado, have invented certain new and useful Improvements in Gaseous-Fuel Heaters and Mixers for Internal-Combustion Engines; and I do declare the following to be a full, clear, and exact description of the invention, such as will enable others skilled in the art to which it appertains to make and use the same.

This invention relates to new and useful improvements in gaseous fuel heaters and mixers for combustion engines and more particularly to such a device for use on automobile engines, the primary object of the invention being to provide a device whereby kerosene distillate or any other inferior oil may be used in place of gasoline which is usually used in devices of this character.

A further object of the invention resides in providing a device which will enable the explosive mixture to be formed instantaneously and which resulting gas will be equally as, if not more, powerful than gasoline which is now used in explosive engines and a further object resides in providing such a device in connection with the exhaust pipe of the engine whereby the heat thereof will be utilized in the compounding of the oil and air into explosive gas.

Still another object of the invention resides in providing a twisted and perforated strip through which the oil and air are directed, such strip being disposed in a housing within the exhaust pipe of the engine.

A still further object resides in providing a device which is simple and durable in construction, inexpensive to manufacture and one which will be very efficient in use.

With these and other objects in view my invention consists of the novel features of construction, combination and arrangement of parts as will be hereinafter referred to and more particularly pointed out in the specification and claims.

In the accompanying drawings forming a part of this application, Figure 1 is a plan view of a gas engine with my invention applied: Fig. 2 is a vertical section taken along the line 2—2 of Fig. 1.

In describing the invention I shall refer to the drawings in which similar reference characters designate corresponding parts throughout the several views and in which

1 designates an internal combustion engine consisting of a plurality of cylinders, 1 having shown four in number but any number may be provided, and connected to said cylinders in the usual or any manner is an exhaust pipe 2. In order to facilitate my invention, this pipe 2 is preferably formed in sections removably secured together, said sections being designated in the drawing as 2^a and 2^b. At the junction of the sections of this exhaust pipe, the latter is slightly enlarged in diameter and at diametrically opposite points thereon said pipe is provided with threaded openings indicated as 3 and 4, respectively. Engaged with the threaded opening 3, which, as shown in the drawing, is at the lower portion of the pipe 2, is an intake pipe 5 which leads from a carbureter 6, the latter being one of any approved type. Mounted in connection with the carbureter 6 is a valve casing 7 in which is arranged a three-way valve 8 and leading to the casing 7 are the supply pipes 9 and 10. The pipe 10 leads to a source of gasoline supply which is provided for use in starting the motor while the pipe 9 leads to a kerosene or distillate supply. The valve has a crank arm 11 connected with one end thereof and pivotally connected to the outer end of the crank arm is an actuating rod 12 which leads to any remote point whereby the valve 8 may be actuated as desired. The use of this valve for the purpose of permitting gasoline to flow to the carbureter and thence to the cylinders will be hereinafter and more particularly referred to.

Connected with the threaded opening 4 which is opposed to the threaded opening 3 with which the pipe 5 is connected, is a pipe section 13 which leads directly to the manifold of the engine whereby to supply the latter with the explosive mixture which is formed in a manner to be presently described. Cast within the enlarged portion of the exhaust pipe 2 at the end of the section 2^b thereof are the centrally converging elbow sections 14 and 15 which connect respectively with the openings 3 and 4. These elbows continuing from the openings 3 and 4 are directed toward the section 2^b and are internally threaded at their ends as shown at 16. Engaged with these threaded ends 16 of the elbow sections are the tubular members or pipe sections 17 which extend longitudinally within said section 2^b. The outer ends of said tubular members 17

are externally threaded and engaged with the threaded ends of a U-shaped bend or union 18 which thus forms a U-shaped casing or housing within the one section of the 5 exhaust pipe. The walls of the members 17 and 18 are spaced from the walls of the exhaust pipe so that the products of combustion may readily pass through the latter but it will be appreciated that by so doing 10 said sections 17 and 18 will be thoroughly heated.

Disposed in each of the arms of this U-shaped member or in other words disposed in each of said members 17 is a twisted and 15 perforated strip 19. The strip in one of the sections 17 is twisted to the right and the other is twisted to the left which enables oil and air passing therethrough to be thoroughly compounded into gas as will appear 20 later.

This invention primarily contemplates the provision of a means for forming gas from oils other than gasoline in order to decrease the expense connected with the running of 25 an internal combustion engine and also to increase the power. In accomplishing this result, my invention also contemplates the using of kerosene, distillate and other inferior oils, as above stated, but inasmuch as 30 the use of such inferior oils requires a certain amount of heat in order to form a perfect gas, I desire to use my invention in connection with the exhaust pipe of the engine so that the necessity for providing some 35 other heating means is obviated. Under such conditions, it will be seen that the engine must be in operation in order to supply such heat to the exhaust pipe and, of course, gasoline must be used in the starting of the 40 engine.

In the operation of the device, the valve 8 is first operated so as to permit a supply of 45 gasoline to flow to the carbureter 6 whereupon the engine may be started in the usual manner and after running for a short time, the products of combustion exhausting through the pipe 2 will thoroughly heat the various members disposed therewithin. The 50 valves may then be disposed so as to cut off the supply of gasoline and permit the oil, such as kerosene, to flow to the carbureter. The oil mixed with the air drawn in through 55 the carbureter will, upon the suction stroke of the piston form a mixture as is done with the use of gasoline. The oil mixed with the air, however, will be directed first through the intake pipe 5 and through the elbow 14 to the section 17 where said mixture is forced 60 through the perforated and twisted strip 19. The mixture is then directed through the bend 18 and returned through the other section 17 to be also forced through the twisted and perforated strip in the latter. In passing 65 through these sections 17 and correspondingly through the twisted strips there-

in the mixture will be thoroughly heated and a perfect explosive gas will thus be compounded. This gas after leaving the last mentioned section 17 is directed through the pipe 13 from which point it is conveyed to 70 the manifold of the engine to be distributed to the cylinders in any approved manner.

From the foregoing it will be seen, that I have provided a simple, inexpensive and efficient means for carrying out the objects 75 of the invention and while I have particularly described the elements best adapted to perform the functions set forth it is obvious that various changes in the form, proportion and in the minor details of construction may 80 be resorted to, within the scope of the appended claims, without departing from the spirit or sacrificing any of the principles of the invention.

Having thus described my invention, what 85 I claim is:

1. In a device of the class described the combination with a casing adapted to be heated and having an inlet and outlet opening intermediate of its ends and at diametrically opposite points therein, centrally converging elbow sections formed integrally with and disposed within said casing and continuing from the openings therein; of a U-shaped mixture carrying pipe section disposed in said casing and having the ends of its arms respectively engaged with the converging ends of said elbow sections. 95

2. In a device of the class described, the combination with a casing adapted to be 100 heated and having an inlet and outlet opening intermediate of its ends and at diametrically opposite points thereon, centrally converging elbow sections formed integrally with and disposed within the casing and continuing from the openings therein, the inner 105 converging ends of said elbow sections being internally threaded, of a pair of tubular arms engaged with the threaded ends of said elbows and continuing longitudinally 110 within the casing in spaced relation to one another, and a U-shaped cap member removably engaged with the opposite ends of said tubular members whereby to form substantially a U-shaped mixture-conducting 115 member in the casing.

3. A device of the character described comprising an elongated cylindrical casing formed of a pair of connected sections disposed end to end, the inner end of the one section having a pair of diametrically aligned openings, inwardly extending elbows formed integrally with the one section and leading from the openings therein toward the other section, and a pair of pipes lying in said last-named section and having their outer ends communicating one with the other, their inner ends being anchored in the free ends of the elbows. 125

4. A device of the character described 130

comprising an elongated casing formed of a comparatively small tubular section and a comparatively large tubular section disposed end to end and connected to each other, the inner end of the smaller section being enlarged and having a pair of openings formed at diametrically opposite points, a pair of elbows formed integrally with said enlarged end of the smaller section and leading therefrom toward the larger section, a pair of pipes disposed within said larger section and having their inner ends threaded into the

free ends of the elbows, and a cap disposed within said larger section and into which the outer ends of said pipes are threaded, 15 whereby they may communicate one with the other.

In testimony whereof I have hereunto set my hand in presence of two subscribing witnesses.

THEODORE H. HABERKORN.
